UNITED STATES PATENT OFFICE.

WARREN J. VAUGHN, OF KANSAS CITY, MISSOURI.

WINDMILL.

SPECIFICATION forming part of Letters Patent No. 278,756, dated June 5, 1883.

Application filed July 11, 1882. (No model.)

To all whom it may concern:

Be it known that I, WARREN J. VAUGHN, a citizen of the United States, residing at Kansas City, in the county of Jackson and State 5 of Missouri, have invented certain new and useful Improvements in Windmills; and I do declare the following to be a full, clear, and exact description of the invention, such as will enable others skilled in the art to which it applies 10 pertains to make and use the same, reference being had to the accompanying drawings, and to the letters and figures of reference marked thereon, which form a part of this specification.

My invention relates to improvements in 15 windmills, and the objects of my improvements are, first, simplicity of construction; second, cheapness; third, greater power according to size and cost; fourth, durability; fifth, ease of regulation; sixth, securing the mill 20 from the danger of being blown off the tower in case of violent wind-storms, which seems the chief trouble with all other mills that have been tried. I attain these objects by the mechanism illustrated in the accompanying drawings, in which—

Figure 1 is a representation of the entire windmill when in operation. Fig. 2 is a rear view, looking onto back of mill, showing fan-frame, hinges, and connections. Fig. 3 is an 30 enlarged view of fan-hinge and end of one of the fan-arms detached. Fig. 4 is a view of the working parts of the machine with the fly-wheel removed. Fig. 5 shows the entire mill when at rest with the rope or wire C pulled 35 down and fastened, allowing the fan-leaves h to be thrown into such a position as to offer no resistance to the wind, as is the reverse when the rope or wire C is loosened, shown in Fig. 1, and by the weight g on the regulating-lever D causes it to drop, and a consequent elevation of the fan-frame, which coming 40 in contact with H, the fan-leaves are presented to the wind and motion is obtained.

Similar letters refer to similar parts throughout the several views.

A represents the tower and table on which the turning frame B rests, and they are connected by a hollow spindle, b, passing through the tower-table A and secured by the nut a 50 underneath.

B is the turning frame, (shown more clearly

in Fig. 4,) which turns only as the wind changes.

C is the power-shaft, with which E and H are connected. It passes through the arm of frame B, and, through the gear-wheels f', transmits the power to the vertical power-shaft b.

D is the regulating-lever, resting on a bolt in a slot in the top of the turning frame B, and having its end forked to fit into a groove in the fan-frame E, for the purpose of throwing the frame into or out of gear, accordingly as it is lowered, as represented in Fig. 1, or raised, as in Fig. 5, which is done by means of rope 65 c being fastened or loosened. As a violent wind-storm increases in velocity its only tendency is to throw this mill out of gear, while the revolutions would remain the same, and even any trouble from that source is anticipated and neutralized by regulating the position of the weight g, which is easily moved back and forth on the regulating-lever D, and may be locked in position by a thumb-screw on it.

75 E is the fan-frame, with connections with H by hinges i, to which the fans h are attached, so that when the fork end of the regulating-lever is lowered, the fork fitting into the groove in the fan-frame E, which slides on shaft C, as seen in Fig. 4, it pulls down the frame E, which throws the fans into a position of non-resistance to the wind, and consequently out of gear, as in Fig. 5.

H is a frame similar to E in construction. 85 It is immovably attached to the end of the power-shaft C, and has the fan-hinges i attached to the ends of its arms, as shown in Fig. 2.

e is a rope or wire passing up through the 90 hollow vertical shaft b, passing on both sides of the inclined power-shaft C, and connects with the regulating-lever D. It is used to raise or lower the forked end of D in order to throw the mill into or out of gear.

95 e are rollers or wheels which assist and steady the movements of the turning frame B and prevent jarring or shaking.

The fan-leaves h are made somewhat concave to catch the wind more than when entirely flat, and they are connected to the frame H by the hinges i.

The frame E slides along the shaft C, while frame H is immovably attached to the end of the same shaft.

- Prior to my invention all or nearly all windmills have been operated on a turn-table, or its equivalent, and have been thrown to the wind by means of a vane or fan-tail. In the case of my improvement there is no vane or tail; but the operation is so easy and simple 10 that it becomes self-adjusting. In other windmills the turn-table turns. In mine it does not, being fast to the tower, and the frame B alone turns. In other mills the fan-leaves are immovable, except in their revolution. In 15 mine, besides the revolution, the attachments E and H, but more particularly E, by the aid of the hinges *i*, can be given the wing motion by means of the adjustable rope or wire *c*, and it matters not whether the mill is in operation.
- 20 The entire mill is constructed of metal, excepting the tower, which, for protection from prairie and other fires, may be constructed of metal also.
- Having thus described my invention, what 25 I claim therein as new, and desire to secure by Letters Patent, is—

1. In a windmill, the combination, with a turning frame, B, a power-shaft passing through one of the sides of said frame, a pivoted regulating - lever provided with an adjustable weight, the inner end of said lever being split 30 to grasp a collar or rim on said shaft, of the tower-table A, around which the frame B turns through the intervention of the friction-rollers *e e*, substantially as and for the purpose 35 set forth.

2. In a windmill, the combination, with the tower-frame A, of the turning frame B, power-shaft, and hollow rope-shaft *b*, the power-shaft being provided with a weighted lever, as de- 40 scribed, and the frames connected by hinged plates *i*, arranged and actuating substantially as and for the purpose set forth.

In testimony whereof I affix my signature in presence of two witnesses.

WARREN J. VAUGHN.
